No. 857,652.

PATENTED JUNE 25, 1907.

T. MUEHLEISEN.
HYDROCARBON BURNER.
APPLICATION FILED DEC. 15, 1906.

UNITED STATES PATENT OFFICE.

THOMAS MUEHLEISEN, OF SAN DIEGO, CALIFORNIA.

HYDROCARBON-BURNER.

No. 857,652.

Specification of Letters Patent.

Patented June 25, 1907.

Application filed December 15, 1906. Serial No. 348,047.

To all whom it may concern:

Be it known that I, THOMAS MUEHLEISEN, a citizen of the United States, residing at San Diego, in the county of San Diego and State 5 of California, have invented a new and useful Hydrocarbon-Burner, of which the following is a specification.

This invention has relation to hydrocarbon burners and it consists in the novel construction and arrangement of its parts as herein-after shown and described.

The object of the invention is to provide a burner adapted to convert liquid fuel such as hydrocarbon oils or vegetable distillates into 15 fuel gas or vapor and consume the same whereby the process of gasification is continued indefinitely and the heat generated may be used for domestic or other purposes.

With these objects in view the burner consists of the apparatus of special construction and arrangement hereinafter described.

In the accompanying drawings:—Figure 1 is a longitudinal sectional view of the burner. Fig. 2 is a top plan view of a deflector with 25 parts broken away. Fig. 3 is a transverse sectional view of the burner cut on the line 3—3 of Fig. 1. Fig. 4 is an end view of the burner. Fig. 5 is a top plan view of a portion of a clamp used upon the burner.

30 The burner proper 1 is adapted to be inserted in the fire box 2 of a stove 3. Said burner proper consists of the substantially cylindrical gasifying chamber 4 to one end of which is attached a fuel supply pipe 5. The

35 baffle plates 6, 6 extend longitudinally of the said chamber 4 and upon the upper plate 6 is located a fuel-receiving pan 7. The end of the pipe 5 terminates over the pan 7 so that the fuel passes from the said pipe into the

40 said pan. The said pipe 5 enters the top of the chamber 4 at a point beyond or outside of the wall of the fire box 2. The exterior surface of the chamber 4 located within the firebox 2 is provided with the longitudinally

45 extending spines or corrugations 8. These corrugations or spines are provided for the purpose of increasing the exterior surface of the said chamber and for retaining the flame in contact with the same. The bottom of

50 the chamber 4 is provided with a gas exit nipple 9 to which is attached the valve casing 10; the needle valve 11 is located in the said casing 10 and when the said valve 11 is closed against its seat the pointed end thereof projects through the said seat and beyond the outer side of the casing 10. Consequently,

each time that the valve 11 is withdrawn from the seat in opening the said valve is cleaned by the edge of the seat of soot or other foreign matter.

6c

The valve stem 12 passes through the tube 13 which is attached at its end to the casing 10. The said stem is provided at its outer end with a handle or wheel 14; the stuffing box 15 is located at the end of the tube 13 and receives the said valve stem 12. The ring 18 is provided with a set screw 19, consequently, when the valve 11 has been opened or closed the set screw 19 may be turned into engagement with the valve stem 12 when the 65 said stem is fixed with relation to the tube 13 as the side of the ring 18 will bear against the stuffing box 15.

The end 20 of the chamber 4 is closed while the opposite end of the said chamber is open 75 but is normally closed by the cap 21. The said cap is provided with an annular flange 22 which receives the end of the chamber 4 and the lead washer or disk 23 is interposed between the end of the chamber 4 and the 80 inner side of the cap 21. The outer side of the chamber 4 is provided with the lugs 24 located diametrically opposite each other. The ends of the clamp 25 pass behind the said lugs 24 and the said clamp is provided 85 at its middle with a threaded stub 26. The longitudinal axis of the said stub is in alignment with the longitudinal axis of the chamber 4. The nut 27 engages the thread of the stub 26 and a washer 28 is interposed between the nut 27 and the cap 21.

It is obvious that by removing the clamp 25 and the cap 21 that the interior of the chamber 4 may be readily reached for the purpose of cleansing the same and removing 95 therefrom residuum or other products of the liquid fuel.

The U-shaped lug 29 is formed upon the under outer side of the chamber 4 and is adapted to support the flame deflector 30. The upper end of the said deflector is 100 provided with a head 31 which enters the space between the lower portion of the lug 29 and the bottom of the chamber 4. The reduced neck 32 enters the space between the 105 ends of the U-shaped portion of the said lug 29. The intermediate portion of the deflector 30 is triangular as at 33, and is disposed directly in front of the gas outlet of the valve casing 10. Thus the flame from said outlet may be split and evenly divided or by 110 turning the said deflector 30 axially the said flame may be diverted to one side or the

other of the fire box 2. The starting pan 34 is located in the fire box 2 under the gasifying chamber 4. The oil supply pipe 35 terminates over the said starting pan 34. The pipe 35 is provided with a valve 36 and connects with the pipe 37. The pipe 5 is provided with a needle valve 38. The pipe 39 is connected at one end with the casing of the needle valve 38 and at its other end with the pipe 37. The said pipe 39 is filled with material 40 which may be asbestos, sand, or other granular or similar material. Said material not only filters the liquid fuel as it passes through the gasifying chamber but serves as a check against the gas pressure generated in the said chamber and prevents said gas pressure from expanding through the oil supply pipe 37 and thus interfering with the feeding of the oil to the burner. The chamber 4 is provided with the lugs 41 which are bolted or otherwise secured to the wall of the fire box 2 whereby the said chamber is fixed with relation to the said fire box. The inner end of the said chamber 4 is supported by a post 42, the lower end of which rests upon the bottom of the fire box 2.

The operation of the burner is as follows: The valve 36 on the pipe 35 is opened and oil passes from pipe 37 to pipe 35 into the starting pan 34. This oil is ignited, and the chamber 4 is enveloped in a flame of high temperature. Thus the said chamber 4 together with the spines 8 and the baffle plates 6 become thoroughly heated. The needle valve

38 is then opened and oil passes from pipe 37 through pipe 39 and granular material 40 to pipe 5. Thence into the chamber 4 and is deposited in the pan 7. The parts having been thoroughly heated as above described, the oil begins to vaporize as soon as it is deposited in the said pan. This vapor arises and comes in contact with the interior surface of the chamber 4 and the surfaces of the baffle plates 6 and is gasified. The gas then passes between the said baffle plates and out of the chamber 4 through the nipple 9 to the valve casing 10 and out of the same through the exit thereof. The gas thus liberated is ignited under the casing 4 and is deflected by the deflector 30 as above described.

Having described my invention, what I claim as new is:—

In a hydrocarbon burner, a gasifying chamber, an oil supply pipe connected therewith, said chamber having a gas exit, a U-shaped lug carried by the chamber, a flame deflector having an enlarged head and a reduced neck which enters the space between the ends of the U-shaped lug, the lower portion of said deflector being triangular in horizontal section.

In testimony that I claim the foregoing as my own, I have hereto affixed my signature in the presence of two witnesses.

THOMAS MUEHLEISEN.
